UNITED STATES PATENT OFFICE.

HUGO LENTZ, OF LEIPZIG-SCHLEUSSIG, GERMANY.

REVERSING-GEAR FOR STEAM OR OTHER ENGINES.

SPECIFICATION forming part of Letters Patent No. 733,058, dated July 7, 1903.

Application filed October 10, 1902. Serial No. 126,718. (No model.)

To all whom it may concern:

Be it known that I, HUGO LENTZ, a subject of the Emperor of Austria-Hungary, and a resident of Leipzig-Schleussig, Saxony, German Empire, have invented certain new and useful Improvements Relating to Reversing-Gear for Steam or other Engines, of which the following is a specification.

This invention relates to a single reversing-gear arrangement with one eccentric only, whereof the distinguishing feature is that the eccentric, which is revoluble on a pivot or pin secured to the distributing-shaft laterally and is provided with segments of an internal (or "nut") screw-thread, is turned on its pivot through the axial displacement of a spindle which is housed within the said distributing-shaft, made hollow for the purpose, and is provided with segments of an outer screw-thread corresponding to the inner screw-threading of the eccentric, the movement thus imparted to the eccentric, being such that in the triangles formed by the lines which connect the center of the eccentric pin or pivot, the center of the distributing-shaft, and the center of the eccentric itself the line extending from the center of the pivot to the center of the distributing-shaft invariably forms the longest side. From the reversing-mechanism hitherto known this arrangement, besides being more simple, differs in this, that it enables the advantages of Stephenson's link-motion to be secured by means of intersecting ("crossed") links or rods, that the adjusting-spindle engages with the eccentric direct, and that the reactive effects of the distributing device are taken up immediately during this engagement instead of being transmitted to the adjusting mechanism, so that even where this improvement is carried out on a very large scale the said mechanism may conveniently and safely be controlled by hand.

In the accompanying drawings, Figure 1 is a cross-section, and Fig. 2 a longitudinal section, of the reversing-gear constructed in accordance with this invention, while Figs. 3, 4, and 5 show the segments of screw-threads of the adjusting-spindle and eccentric. Fig. 6 is a diagram of the reversing-gear superposed to serve for a single slide-valve, and Fig. 7 represents the slide-valve itself.

The sole eccentric which this reversing-gear comprises, marked *a*, and having its center at *m*, is revoluble on a pivot or pin *b*, secured laterally to the distributing-shaft *c*, so that the said center *m* of such eccentric, similarly to the imaginary eccentric in a Stephenson link-motion with intersecting links, may be moved through an arc *m m' m* convex in relation to the center *x* of the distributing-shaft *c*, or, to express it geometrically, so that in the triangles *x b m* formed at any time by the center *m* of the eccentric, the center *x* of the distributing-shaft, and the center of the eccentric-pin *b* the line connecting the center of the pin *b* and the center *x* of the distributing-shaft invariably constitutes the longest side of the triangle.

Within the hollow distributing-shaft *c*, which is suitably notched or recessed at the point where the eccentric *a* is situated, there is inserted the adjusting-spindle *e*, which a suitable device—such as a guiding-wedge *f*, for example—prevents from being turned out of position while it is adjustable in the direction of the axial line of the distributing-shaft *c*. The said adjusting-spindle *e* forms a segment of a many-threaded screw (see Figs. 3 and 4) the axis of which coincides with that of the pin *b*. Fig. 3 presents the screw-thread (here supposed to extend all around, though in the mechanism it is of course incomplete) from which the adjusting-spindle *e* must be assumed to have been cut out. The eccentric carries a segment of a nut or inner screw-thread *g*, corresponding to the above-mentioned (outer) screw-thread, the axis of which, therefore, likewise coincides with that of the pin *b*. Thus it will be seen that by an axial displacement of the adjusting-spindle *e* and through the agency of the screw-threads the eccentric *a* will be caused to perform a rotation on its pin *b*, and the center *m* of such eccentric be thereby displaced, the positions *m* and *m'* corresponding to a "full charge," forward or backward, as the case may be, while the position *m⁰* corresponds to the "zero charge," so that, as will be seen from Fig. 5, this reversion will produce a distribution of steam alike to that which would be caused by a Stephenson link-motion with crossed eccentric-rods, whereof the peculiarity is that as the charge decreases the linear lead also di-

minishes, and by the time eccentricity becomes smallest—*i.e.*, comes to the zero-point—also reaches zero, or the point corresponding to an absolute zero charge.

5 It will be seen that the several teeth (here termed "segments" of screw-threads) do not, as in toothed wheels, meet along one line only, but in all cases cover each other's entire surface, so that the specific pressure mutually exercised by them becomes very small and any wear, so far as these teeth are concerned, is practically out of the question, and it will further be seen that the reacting forces brought to bear upon the valve-spindle by 10 the operation of the reversing device, through the medium of the eccentric, are taken up by the screw-thread segments of the adjusting-spindle *e* and are not, therefore, further transmitted to the parts whereby the said spindle 15 is adjusted. Besides, those reactive forces may be reduced at will by adequately determining the pitch of the screw-threads. An advantageous arrangement is that in which more than one reversing mechanism, such as 20 25 is herein described, would be controllable from one eccentric and through one adjusting-spindle only.

Having now described my invention, what I claim as new, and desire to secure by Letters Patent, is—

In a reversing-gear for engines, the combination of a tubular shaft having a lateral offset carrying an eccentrically-located supporting-pivot, a shiftable eccentric wheel carried by the offset portion of the shaft and having an eccentric mounting upon the said supporting-pivot, said eccentric having an opening formed along one edge thereof with a series of internal screw-thread segments, and a longitudinally or axially adjustable spindle 35 40 45 slidably interlocked with the tubular shaft inside of the latter and held by the interlocked connection to a fixed reciprocatory movement, the said spindle being provided thereon with a series of external screw-thread segments slidable between and against those of the eccentric wheel, substantially as set forth.

In witness whereof I have hereunto set my hand in presence of two witnesses.

HUGO LENTZ.
